HOLDER FOR POSTAGE STAMPS IN ROLL FORM

Harvey Lathrop, Forest Hills, N. Y.

Application October 11, 1951, Serial No. 16,909

Term of patent 14 years

(Cl. D74—1)

To all whom it may concern:

Be it known that I, Harvey Lathrop, a citizen of the United States, and a resident of Forest Hills, county of Queens, and State of New York, have invented a new, original, and ornamental Design for a Holder for Postage Stamps in Roll Form, of which the following is a specification, reference being had to the accompanying drawings, forming part thereof.

Figure 1 is a perspective view of a holder for postage stamps in roll form, showing my new design, the broken lines being for illustrative purposes only; shown in opened condition in readiness for loading.

I claim:

The ornamental design for a holder for postage stamps in roll form, substantially as shown and described.

HARVEY LATHROP.
